UNITED STATES PATENT OFFICE.

JAMES S. SHOEMAKER, OF HAMMOND, INDIANA, ASSIGNEE OF ONE-THIRD TO LLOYD W. PARSONS, OF HAMMOND, INDIANA.

DEVICE FOR HEATING AIR-BRAKE SYSTEMS.

1,079,611.

Specification of Letters Patent.

Patented Nov. 25, 1913.

Application filed May 20, 1912. Serial No. 698,454.

To all whom it may concern:

Be it known that I, JAMES S. SHOEMAKER, a citizen of the United States, residing at Hammond, in the county of Lake and State 5 of Indiana, have invented certain new and useful Improvements in Devices for Heating Air-Brake Systems, of which the following is a specification.

This invention relates to an improvement 10 in devices for heating air-brake systems, particularly adapted for the purpose of preventing the air conducting and operative parts of the system from freezing.

In the use of air-brake systems, the air 15 being under compression, the moisture in the air condenses in the pipes and freezes in cold weather, and if such freezing occurs at a vital point, as a bend in the pipe, as at the couplings, or at some operative part 20 of the system, the brakes may fail to work. Should the freezing occur in a coupling, as between the tender and next coach, the entire system would be rendered inoperative.

The object of the present invention re- 25 sides in the provision of means whereby the air is heated as it passes from the main reservoir on the engine into the system.

A further object of the invention resides 30 in the utilization of the exhaust steam from the air-pump as the heating medium, and this particularly for the reason that the action of the pump is automatically regulated by the pressure of air in the reservoir, in consequence of which exhaust steam will 35 be fed to the heating chamber simultaneously with and with the same frequency as the operations of the brakes, each reduction of air-pressure automatically starting the air-pump, whereby the heating device 40 would not only be self-regulating, but only so much steam utilized as would be necessary for the purpose, and without adding to the operating expense of the locomotive.

Figure 1 is a view in elevation partly in 45 section illustrating the improved heating device. Fig. 2 is a broken elevation illustrating conventionally a well known type of automatic controlling means for the pump by the pressure in the reservoir.

In the accompanying drawing, showing a 50 preferred embodiment of my invention, the reference numeral 1 represents the air-pump on a locomotive operated by steam, the particular type of pump being immaterial, and 55 by which a storage reservoir 2 is supplied

by air under pressure, a pipe 3 furnishing communication between the pump and reservoir, the relative location of the pump and reservoir also being immaterial, and which may be positioned on the locomotive 60 as may be most convenient and practicable.

Suitably mounted on the locomotive is a heating tank 4, preferably cylindrical in form, one end of which has connection with the exhaust port of the air-pump, as by a pipe 5, and the opposite end of which has a pipe 6, preferably leading to the smoke-stack, or through which the steam may pass direct to the atmosphere. Disposed within the heating tank is a coil of pipe 7, 70 having communication with the air reservoir 2 by means of a pipe 8, and with the train pipe by a pipe 9, the air passing from the air reservoir through the coil, which is heated by the exhaust steam from the air-pump passing through the heating tank, and thence into the train-pipe (not shown), to the brake operating appliances. 75

By the novel arrangement and co-operation of elements above described, I provide 80 an efficient and simple means for heating the air as it passes from the main air-reservoir into the train pipe, and as the air-pump on a locomotive is seldom inactive, at least not for any extended period of time, and as 85 the consumption of air automatically regulates the operation of the air-pump the heating tank is automatically supplied with exhaust steam for heating the coil therein at each operation of the pump, thus heating 90 the air without any added expense, and without requiring any attention or regulation whatever on the part of the engineer or fireman.

A type of automatic air-pump control by 95 the reservoir pressure is illustrated in Fig. 2, and indicated generally by 10, no further detailed description being deemed necessary.

Having thus described my invention, what is claimed is:

1. A device of the character described, the combination with an air-brake system comprising an air-pump operated by steam, a main air reservoir, a pipe connecting said reservoir with the train pipe and provided 105 with a plurality of coils, a heating tank within which said coils are disposed, and means for supplying said tank with exhaust steam from the air-pump.

2. A device of the character described, the 110

combination with an air-brake system, comprising an air-pump operated by steam, of a main air-reservoir supplied with air under pressure by said pump, the pressure of air automatically controlling the operation of said pump, means for supplying the brake operating means with air from said reservoir, and means for heating said air with the exhaust steam of the pump, whereby the

operation of the pump and supply of heating medium are both controlled by the variable pressure of the air. 10

In testimony whereof I affix my signature in presence of two witnesses.

JAMES S. SHOEMAKER.
